DUPLICATING MECHANISM

Tracy F. Brackett, Detroit, Mich., assignor to
 General Motors Corporation, Detroit, Mich., a
 corporation of Delaware

Application February 13, 1941, Serial No. 378,706

6 Claims. (Cl. 99—13.5)

The invention relates to mechanism for reproducing a surface and is an improvement over the co-pending application Serial No. 156,644, filed July 31, 1937 in my name, entitled "Photo-cell control for die-sinking machine" which has become Patent Number 2,242,506. That application discloses means whereby any contour or shape may be reproduced from a model by driving a tracer head over the surface of the model and controlling cutting mechanism by the variations in the travel of the tracer. It has been customary in devices of this kind to use a router or round end end-mill to cut the surface of the blank to reproduce the original model and this leaves a series of curved grooves on the surface of the generated model as the cutter is fed across said surface. It is therefore necessary after the generated model has been roughly completed by this means to perform another operation thereon to smooth down the surface, such as sanding, etc.

If, however, a different type of cutting mechanism is used, such as a cylindrical rotating cutter similar to that used on planers and joiners, then the angularity of the cutter must be altered as well as its longitudinal position before a satisfactory model can be generated. The use of a cylindrical cutter will eliminate ridges and provide a substantially smooth generated surface.

It is therefore an object of my present invention to provide means using a rotating cutter whose tangency to a desired generated surface will be maintained and its position varied, depending upon the curvature of the original model, so that the same will be tangent at all times to the desired generated surface and thus avoid the above mentioned ridges and grooves and provide a substantially smooth generated surface.

It is a further object of my invention to provide rotating cutting means which will be maintained tangent to a compound curved surface.

With these and other objects in view, the embodiments of my invention will be best understood by reference to the following specification and claims and the illustrations in the accompanying drawings, in which

Figure 1 is a side elevation of a model reproducing machine, similar to that shown in Serial No. 156,644, showing my invention applied thereto;

Figure 2 is a top plan view of the same machine;

Figure 3 is an enlarged detailed view showing

the follower or tracer mechanism which rides along the surface of the original model;

Figure 4 is a sectional view taken on line 4—4 of Figure 3;

5 Figure 5 is a sectional view taken on a portion of line 5—5 of Figure 3;

Figure 6 is an enlarged detailed vertical view showing the cutting means controlled by the tracer; and

10 Figure 7 is a view taken at right angles to Figure 6 showing the same cutting mechanism.

Referring now more specifically to the drawings, there is shown in Figure 1 a stationary box frame 2 within which is mounted for longitudinal movement with respect thereto a smaller sub-frame 4 which is driven by suitable apparatus housed within the enclosure 6 and driving a rotatable shaft 8 engaging a portion of said frame. There is mounted upon suitable stationary structure 10 a master model 12 and also at the opposite end of the stationary frame a supporting member 14 which has mounted thereon a blank 16 in which may be cut the surface it is desired to reproduce. A tracing mechanism, generally indicated at 18, is mounted on a vertical support 20 carried by the movable frame, said vertical rod being capable of transverse movement across the movable frame and being driven by mechanism housed within the enclosure 22 driving through shafts 24 and 26. The follower mechanism may also be driven vertically on the shaft 20 by a threaded rod 28 driven by mechanism housed within the enclosure 30. It is thus possible to drive the tracer mechanism in any one of three directions by the means 6, 22 and 30 respectively.

Whichever driving means is being used for the scanning direction simultaneously drives a similar mechanism carrying the cutting means which is shown as a vertical column 32 similar to 20 carried by the movable frame and which carries the cutting mechanism indicated generally at 34, the same being driven vertically by a threaded rod 36 which is operated synchronously with the threaded rod 28 and is driven transversely across the frame by a threaded rod 38 which is driven synchronously with the threaded rod 26 driving the tracer. Since this column 32 is also carried by the movable frame, it is obvious that it will be moved longitudinally at the same time that column 20 is so moved.

The operation of such a type of device as described in S. N. 156,644 is that the tracer, and, of course, the cutter, are placed in one extremity of

the model to be reproduced and the blank, respectively, and then let us say that the driving means 22 is energized to cause the tracer member and the cutter to move transversely across the machine, the tracer, being in contact with the master model as it is driven transversely, in following the model contour moves in and out or longitudinally of the whole structure. This movement in and out controls the longitudinal driving means 6 to move the whole movable carriage, thus moving the cutter to follow a similar contour in the blank and at the same time correct to bring the tracer back to a position where it will no longer call for movement. However, in scanning the master surface and in cutting the blank with a round end end-mill, as the cutter moves back and forth across the model ridges will be left in the blank as the surface is generated by the end-mill. I therefore use a cylindrical rotating cutter to cut the surface to overcome this disadvantage.

Referring now more specifically to Figures 6 and 7, there is shown therein mounted upon the vertical column 32 a slidable sleeve 40 to which is integrally secured a horizontal tube 42 which extends on both sides of the column 32, one end carrying internally threaded means 44 which engages the threaded rod 36 to cause the device to be driven vertically, if desired, and the opposite end carrying a sleeve 46 which has a plurality of ears or lugs extending therefrom to support desired apparatus. One angled member 48 has secured thereto by suitable bolts 50 a small control motor 52. Extending upwardly from said sleeve 46 is an arm 54 which pivotally supports a long crank arm 55 at a proximate center point, said arm supporting in turn a second driving motor 56 which rotates the cutter member 58 per se.

A third projecting flange 60 supports on its outer end a bushing 62 within which is mounted one section of a rotatable cylindrical member 64 which is made integrally with a worm wheel 66. Through the center of the compound member 64-66 is drilled an opening 68 which is internally threaded and through which is screwed one end of an eye bolt 70. The threaded portion of the worm wheel 66 engages with a worm 72 mounted on the shaft 74 of the motor 52 and is adapted to be driven thereby. The outer surface of the member 64 which projects through the bushing 62 is externally threaded as shown at 76 and a large nut 78 is applied thereto to hold the member within the bushing but is not tightened to an extent which will prevent 64 from turning, but only to keep it snug.

Projecting from one side of the motor housing of the motor 56 is a pin 80 which projects into the eye 82 of the eye bolt 70 and thus causes the motor 56 to pivot around its support as the eye bolt is forced up or down as shown in Figure 6. The end 86 of the arm has secured thereto one end of a Bowden wire 88 by a suitable set screw 90. The exterior cable 92 of the Bowden wire is supported by a bracket 94 from the motor housing 52. This Bowden wire assembly continues over to the tracing mechanism. It is thus evident that when the motor 52 is energized the worm 72 driven thereby will cause the worm wheel 66 to rotate and thus cause the threaded portion of the eye bolt 70 to be driven upwardly or downwardly, depending upon the direction of rotation and thus adjust the position of the motor 56 and its associated cutter 58 as desired. At the same time that this is done the Bowden wire telegraphs the action back to the tracer so

that only a sufficient amount of correction will be applied at one time.

The tracer mechanism on the other hand is best shown in Figure 3 and there again we have the vertical column 20 around which a slidable sleeve 96 is applied and which again carries a horizontal rod 98, one end of which supports an internally threaded member 100 which is associated with the vertical driving threaded means 28 to move the assembly up and down on the column 20. A supporting member 102 is applied to the opposite end of the transverse rod 98 and is secured thereto by a suitable set screw 104, the upper portion of the member 102 being drilled out to form a cavity 106 within which is pivoted a bell crank 108 engaging a motion transfer rod 110 on the control mechanism. There is also provided a longitudinal bushing 112 which supports the shaft 114 of a plunger member which transmits follower motion to the control.

The lower portion of the supporting member 102 is in the nature of a plate surface 118 which carries thereon certain switching means pivoted about the axis of a bolt 120. This switching means comprises an elongated flat lever 122 which is pivoted about said bolt as best shown in Figure 5, and is biased toward its uppermost position by a suitable leaf spring 124 which is anchored on the plate 118. Mounted on this plate 122 are two spaced contact switch members 126 and 128 and secured to one corner is the opposite end of the Bowden wire 88, the exterior stationary portion 92 of which is secured to the plate 118. Also pivotally mounted on the bolt 120 around a sleeve 130 is a bell crank member 132, one end of which supports a cylindrical tracer 134, said follower 134 having a shaft 136 which projects down into an opening in the upper end of the bell crank lever and is mounted upon a pair of ball bearing assemblies 138 for easy rotation. The end of the plunger 114 is adapted to ride against the side of the bell crank lever 132 to hold the tracer 134 under some slight pressure against the side of the master model and transmit its motion to the control means.

The opposite end of the bell crank lever contains a switch point 140 which oscillates between the two switch points 126 and 128 carried on the pivotal plate 122. It will thus be evident that as the tracer 134 is driven, let us say transversely across the surface of the master model, the contour thereof will force it back and cause the bell crank 132 to rotate about the pivot point of the bolt 120. Let us assume that the contour forces the assembly counterclockwise as shown in Figure 3 which will cause switch point 140 to make contact with switch point 126; this will energize the motor 52 and cause the same to rotate in such a direction that the threaded portion 70 of the eye bolt will be drawn down to rotate motor housing 56 counterclockwise about its pivot, as shown in Figure 6, and pull the rotating cutter 58 slightly away from the blank and thus cause the same correction that the tracer has called for. The motor 52 is rotatable in either direction, depending upon which circuit is made. However, when the motor housing 56 makes this particular motion it pulls the Bowden wire 88 outwardly from the sleeve 92, which motion is translated to the tracer in which the wire 88 is pulled downward to move the plate 122 counterclockwise around the pivot 120. This tends to move contact 126 away from contact 140 and when the plate 122 has moved far enough to break the contact the motor 52 will be deenergized and the cutter will

remain in this position until further tangential correction is called for by movement of the tracer 184. Of course at the same time the transfer rod 114 has caused the movement of the control rod 116 to actuate the driving means 6 for longitudinal travel of the movable frame to make whatever longitudinal correction of the tracer and cutter is necessary.

It should also be pointed out that the tracer roller and the cutter are the same size and character, are located on their mountings at the same distance from the pivot point and are initially positioned in the same upright position so that the surfaces traced and generated will be as near identical as possible.

I claim:

1. In a device of the class described, a model having a curved surface that it is desired to reproduce, a cylindrical roller tracer pivotally mounted to engage said surface, a cylindrical rotary cutter independently pivotally mounted to engage a blank to be cut means to simultaneously move both the tracer and cutter across the model and blank respectively and means interconnecting said tracer and cutter to cause one to move if the other is forced about its pivot.

2. In a device for reproducing surfaces, a cylindrical tracer head, means for mounting said head to roll over a surface, pivotal means for said mounting, means for driving said tracer head across said surface, whereby as it travels thereover it will move pivotally, a cylindrical cutter independently similarly pivotally mounted to cut a generated surface on a blank, means simultaneously moving said cutter with said tracer and means interconnecting said tracer and said cutter whereby any pivotal movement of the tracer as it is moved will cause the cutter to duplicate such pivotal movement to maintain the same in a tangential position with respect to the surface being developed.

3. In a surface reproducing device having a model and a blank mounted in spaced relation, a cylindrical tracer head pivotally mounted adjacent the model tangent to the surface thereof, a cylindrical cutter independently pivotally mounted adjacent the blank substantially tangent thereto, means for simultaneously moving the

tracer and cutter across the model and blank respectively and means interconnecting the tracer head and cutter to cause one to move about its pivot if the other rotates about its own and thus remain substantially parallel.

4. In a surface reproducing device having a model and a blank mounted in spaced relation, a carriage movable in a plane normal to the surfaces of the model and blank, a rotatable cylindrical tracer head pivotally mounted on the carriage adjacent the model so that its cylindrical surface rolls on the model surface and is substantially tangential thereto, a rotatable cylindrical cutter pivotally mounted on the carriage 15 adjacent the blank in substantial tangential contact therewith, and means interconnecting the pivoted tracer head and cutter to transmit any rotation of the tracer head about its pivot to the cutter head so that the two will remain in substantial parallelism at all times.

5. In a surface reproducing device having a model and a blank mounted in spaced relation, a carriage movable in a plane normal to the surfaces of the model and blank, a rotatable cylindrical tracer head pivotally mounted on the carriage adjacent the model so that its cylindrical surface rolls on the model surface and is substantially tangential thereto, a rotatable cylindrical cutter pivotally mounted on the carriage 25 adjacent the blank in substantial tangential contact therewith, means to move said cutter about its pivot and means operated by the position of the tracer head to control the last-named moving means.

6. In a surface reproducing device having a model and a blank mounted in spaced relation, a carriage movable in a plane normal to the surfaces of the model and blank, a rotatable cylindrical tracer head pivotally mounted on the carriage adjacent the model so that its cylindrical surface rolls on the model surface and is substantially tangential thereto, a rotatable cylindrical cutter pivotally mounted on the carriage 30 adjacent the blank in substantial tangential contact therewith, electrical means to move said cutter about its pivot and switching means actuated by the tracer head to control the electrical means.

TRACY F. BRACKETT.
